UNITED STATES PATENT OFFICE

2,518,654

AUTOMATIC CONTROL FOR BOILER FEED
PUMPS

Louis P. Backus, Philadelphia, Pa.

Application October 13, 1947, Serial No. 779,448

2 Claims. (Cl. 103—14)

1

This invention relates, in general, to means for maintaining a predetermined head or level of water in a steam generating boiler, and has for its principal object the provision of a simplified apparatus of the kind indicated.

A more particular object of the invention is to provide an inexpensive, simplified device, which may be attached to substantially any type of steam generating boiler, industrial or domestic, for the purpose of automatically regulating the feed of water into the boiler, in order to maintain a predetermined safety level of water therein.

A specific object of the invention is the provision of a simplified automatic control for the water feed pump of a steam boiler.

A further object is to provide a device of simplified design and inexpensive construction, and applicable to substantially all types of steam generating boilers.

Additional objects and advantages will appear as the description proceeds, and will be best understood by reference to the drawings, wherein:

Fig. 1 is a vertical, sectional view, partly in elevation, of an embodiment of the invention, operatively coupled to the water-supply pump of a steam generating boiler;

Fig. 2 is a plan view of a component part of the slide valve assembly; and

Fig. 3 is a perspective view of the water level float and the attached slide valve means.

In the drawings, 10 designates a casing having a cap 11 threadedly secured thereto and provided with an opening which accommodates a pipe 12 communicating with a steam generating boiler (not shown). Within the upper portion of the chamber of the casing 10, a valve member, indicated generally at 13, and having a disc-like configuration, is fixedly secured in any suitable manner, as by a drive fit.

The valve member 13, which is formed with a central opening 13a, is provided with a marginal opening or outlet port 14 which, as hereinafter described, may be aligned with an outlet or valve opening 15, to which a pipe 15a is secured; the pipe 15a also being secured to a steam-operated water pump, indicated generally at "P" and connected in turn with the above-mentioned boiler. A manually controlled valve, indicated generally at 16, in the pipe line 15a, affords means to restrict the volume of steam from the casing chamber to the said water pump.

By inspection of Figure 2, it will be noted that the valve member 13 is provided with two inwardly directed slots or grooves 17, 18 arranged in opposed relation, the slot 18 being adjacent to

and aligned with the outlet port 14 of the said member. The opposed slots 17, 18 function as guides or slide runways for shoes or plates 19, 20 arranged in spaced, opposed relation and fixedly joined by a web or strut 21 having a reinforced central portion, as at 22. To the central portion 22 of the web or strut 21, the upper end of a valve stem or rod 23 is fastened, the lower end of the said rod being threadedly secured to a hollow ball float 24. The shoes 19, 20, with their joining strut 21, together with the valve stem 23 and the ball float 24, constitute a movable valve assembly "A," which coacts with the seat of the valve opening 15 to admit steam into the pipe 15a and thence through the normally open valve 16 to the pump "P." When the shoe 20, as described hereinafter, is raised sufficiently to close the valve opening 15, it will be understood that the operation of the pump will be stopped, or until the level of the water in the boiler and consequently the casing has permitted the float 24 to descend to a point where the attached stem and valve shoe 20 reopens the said valve. With a view to maintaining the float 24 in alignment with the inner surface of the wall of the casing, the exterior periphery of the float may be provided with beads or protuberances, as at 25.

The casing 10 is also provided with a water inlet opening 26, which is connected by the pipe 27, elbow 28, and longitudinally extending pipe 29 to the lower or water containing portion of the steam generating boiler (not shown).

The function and mode of operation of the device have been in large measure indicated above, but may be summarized as follows:

With a given level of water and a predetermined pressure of steam, the water will rise in the casing 10 to the same height as in the boiler, and since the force exerted by the steam entering the casing through the pipe 12 is counterbalanced by the equal pressure of the water from the same boiler, the float 24 is free to rise with the column of water in the lower portion of the casing. In the position illustrated in Figure 1, it will be noted that steam entering through the pipe 12 may still pass out through the opening or port 14 in the valve member 13, and thence through the partially open valve opening 15 and the water pump, via the pipe 15a and valve 16, the pump "P" then forcing water into the boiler. This operation, it will be understood, will be continued until the float 24 raises the shoes 19, 20 to a position where the valve shoe 20 fully closes the outlet or valve port of the casing. The generation of steam will continue until the level of

water again falls to a point where its corresponding head in the lower part of the casing 10 allows the float 24 to again move the right-hand valve element 20 to a point effective for partially opening the steam outlet port of the casing, when the same cycle of functions described above will commence. It is to be further understood that the radius of curvature of the ball float 24 will permit it to rest on the top of the water supply pipe 26 without obstructing the flow of water either into or out of the casing 10.

It will be observed that the design and construction are of the utmost simplicity, and of such a type that the device may readily be applied to not only stationary and mobile steam engines, but also to standard industrial types employed in the steam generation of power, or for steam heating purposes. The device also lends itself to the convenient and economical control of domestic steam heating installations with a minimum of change to existing installations.

While certain preferred embodiments of the invention are hereinbefore set forth, it is to be clearly understood that the invention is not to be limited to the exact construction illustrated and described because various modifications of the details may be provided in putting the invention into practice within the purview of the appended claims.

What is claimed is:

1. In an automatic control for the water pump of a steam boiler, the combination of: a cylindrical casing having a bottom formed with a water inlet and a top formed with a steam inlet, a ring-like valve member secured to said cylindrical casing and having a valve opening in alignment with a corresponding opening in the wall of said casing, and adapted to communicate with said water pump, said ring-like valve member being formed with slideways parallel to

the axis of said casing, a valve member including slides reciprocal in said slideways and one of which is adapted to close said opening in the ring-like valve member, a ball float in said casing above said bottom, and a link connecting said float to said valve member having the sides.

2. In an automatic control for the water pump of a steam boiler, the combination of: a cylindrical casing normally assuming a vertical position, a flat bottom for said casing formed with a circular opening adapted to function as a water inlet, a cover for the other end of said casing having a steam inlet, a ring-like valve member secured to said cylindrical casing and having a valve opening in alignment with a corresponding opening in the wall of said casing, and adapted to communicate with said water pump, said ring-like valve member being formed with slideways parallel to the axis of said casing, a valve member including slides reciprocal in said slideways and one of which is adapted to close said opening in the ring-like valve member, a ball float in said casing adapted to rest on said bottom and having a curvature leaving the opening in said bottom, at least partially open when said ball rests thereon, and a link connecting said ball float to said valve member carrying the slides.
